UNITED STATES PATENT OFFICE

AMBROSE C. MOORE, OF CHICAGO, ILLINOIS, ASSIGNOR TO CHICAGO RAILWAY EQUIPMENT COMPANY, OF CHICAGO, ILLINOIS, A CORPORATION OF ILLINOIS

BRAKE BEAM SUPPORT

Application filed January 6, 1928. Serial No. 244,787.

The invention relates more particularly to that class of brake beam supporting means commonly termed third point supports or fourth point supports, examples of such type of supports being illustrated in Patent No. 997,922, Kiesel, July 11, 1911, and No. 1,114,210, Williams, October 20, 1914.

In third or fourth point supports for brake beams, it is a common practice to support and guide brake beams by means of inclined spring tracks, between which and the brake beams are interposed shoes or carriers that travel upon such tracks. In some instances, the shoes or carriers are secured to the tracks in such manner that while being freely movable lengthwise thereof, the danger of their becoming displaced from the tracks is avoided. In practice, it is found that the brake beams by reason of their connections have a tendency to move lengthwise of the beam, this movement usually being from three-fourths of an inch to an inch from the normal path of movement of the beams along the tracks in the operation of applying and releasing the brakes. Recognizing this tendency of the brake beams to move in endwise direction, it is the practice in some instances to provide the upper portions of the shoes or carriers that travel upon the spring tracks with open seats that will allow for the endwise play or movement of the tension members therein. In practice, it is found that there is a tendency, under the strains and stresses to which cars, and particularly freight cars, are subjected, for the tension members or portions of the brake beams to be thrown out of the open seats of the shoes or carriers.

The main object of my present invention is to provide means whereby the danger of the tension members or portions of the brake beams being accidentally thrown from the seats of the shoes or carriers will be avoided, while at the same time provision is made for permitting the necessary endwise movement of the brake beams, i. e., a movement transverse to the supporting spring tracks. To this end, the invention consists in the features of novelty hereinafter described, illustrated in the accompanying drawings, and particu-

larly pointed out in the claims at the end of this specification.

In the drawings:

Figure 1 is a plan view showing the central portion of a brake beam embodying my invention and showing also a part of the adjacent spring plank and spring track. 55.

Figure 2 is a view in vertical section on line 2—2 of Figure 1.

Figure 3 is a view in vertical section on line 3—3 of Figure 1. 60

Figure 4 is a plan view showing a modified form of the invention.

Figure 5 is a view in vertical section on line 5—5 of Figure 4. 65

Figure 6 is a view in vertical section on line 6—6 of Figure 4.

Figure 7 is a view similar to Figure 6, but showing a modified form of the invention.

Figure 8 is a view in side elevation of the parts shown in Figure 7. 70

Figure 9 is a plan view showing my invention as applied to what is commonly termed a fourth point support.

Figure 10 is a view in vertical section on line 10—10 of Figure 9. 75

Figure 11 is a view in vertical section on line 11—11 of Figure 9.

Figure 12 is a plan view showing a modified form of a fourth point support. 80

Figure 13 is a view in vertical section on line 13—13 of Figure 12.

Figure 14 is a view in vertical section on line 14—14 of Figure 12.

In the form of the invention illustrated in Figures 1, 2 and 3 in which is shown what is commonly termed a third point support, 1 designates the usual spring plank of a car truck from which projects the usual spring track 2 having an inclined portion for sustaining and guiding the brake beam. As shown, the brake beam comprises a compression member 3 and tension member 4, between which extends the strut 5. 85

Upon the spring track 2 is mounted the shoe or carrier 6 that is connected to both the spring track and the brake beam. As shown, the shoe or carrier 6 comprises an expanded lower portion 7 having a slot 8 therein through which the spring track 2 100

passes. As shown, the upper portion of the shoe or carrier is formed with upstanding end walls and with upstanding lugs 9, 10 and 11. The distance between the lugs 10 and 11 is such as to permit these lugs to straddle the end of the strut 5 that is formed with the usual seat to receive the tension member 4 of the brake beam. The lug 9 of the shoe or carrier projects upwardly in front of the tension member 4 and the end of the strut 5. In order to securely retain the tension member 4 and the end of the strut 5 within the upper portion of the shoe or carrier, the lugs 9, 10 and 11 are made of such length and of such material (preferably as a malleable casting or a forging) that when the parts are assembled the upper end of the lug 9 may be bent (from the vertical position shown by dotted lines, Figure 2), over the tension member 4, and the upper ends of the lugs 10 and 11 may be bent (from the position shown by dotted lines, Figure 2), down upon the top of the strut 5, so that all danger of the shoe or carrier becoming disengaged from the brake beam will be prevented. In order to allow for the endwise movement of the brake beam with respect to the track 2, the slot 8 through which this track passes is made very much broader than the track; that is to say, there is a clearance between the side edges of the track 2 and the ends of the slot 8 at each side of the track of approximately three-fourths of an inch.

In the form of the invention illustrated in Figures 4, 5 and 6 of the drawings, the lower portion 7^a of the shoe or carrier is shown as formed with a slot 8^a that is but slightly wider than the width of the track 2. With this form of the invention, in order to allow for the endwise movement of the brake beam, the upper portion of the shoe or carrier is formed with upstanding end walls and with lugs 9^a, 10^a and 11^a, the upper ends of which lugs are adapted to be bent downwardly and inwardly a sufficient distance to retain the shoe or carrier in position upon the brake beam, while at the same time allowing a free endwise movement of the brake beam to a sufficient extent (say, about three-fourths of an inch) in each direction. In order to permit this free endwise movement of the brake beam, it will be noticed that the upstanding end walls of the shoe or carrier are so wide apart that there will be a clearance of about three-fourths of an inch between the sides of the strut 5 and the end walls; and it will be noticed also that there is sufficient space between the bent over lugs 9^a, 10^a and 11^a to allow free lateral movement of the parts.

In the form of the invention shown in Figures 7 and 8, the construction of the lower part of the shoe or carrier is similar to that illustrated in Figures 4, 5 and 6; that is to say, the shoe or carrier has a lower portion 7^a with a narrow slot 8^a therein, through

which passes the spring track 2. In this form of the invention, there are vertical lugs or side members 14 and 15 rising from the shoe or carrier at the sides of the strut 5, and there is a vertical lug or end member 16 opposite the outer end of the strut 5. The lugs or side members 14 and 15 are spaced at a sufficient distance apart to permit the free endwise or lateral movement of the brake beam, hereinbefore referred to, and the lug or end member 16 is at a distance from the free end of the strut 5 so as not to interfere with such lateral movement of the brake beam. In order to retain the tension portion of the brake beam in engagement with the shoe or carrier, there is provided a bar 17 that extends between the upper ends of the lugs or side members 14 and 15, and the upper ends of these lugs or side members 14 and 15 are preferably bifurcated and perforated, as shown, to receive the ends of the locking guard bar 17, and to receive suitable pins, rivets or the like to hold the bar 17 in engagement with the lugs 14 and 15. As shown, one end of the guard bar 17 is pivotally connected to a lug 14 by a rivet 18 so that the guard bar can be swung from the position shown in dotted lines to the position shown in full lines in Figure 7, and when in the closed position shown by full lines in Figure 7, the guard bar 17 can be held in place by a suitable rivet, bolt or pin 19.

In the form of the invention illustrated in Figures 9, 10 and 11, my invention is shown as applied to what is commonly termed a fourth point support for brake beams. In this embodiment of the invention, there will be a supporting spring track 2 at each side of the center of the brake beam. One only of such tracks and the shoe or carrier thereon is illustrated in the drawings, as it will be understood that a similar track and shoe will be provided at the opposite side of the brake beam strut 5. In this form of the invention, the lower portion 7^a of the shoe or carrier is provided with a comparatively narrow slot through which the spring track 2 passes, this slot being of proper dimension to permit the shoe or carrier to move longitudinally of the track. As shown, the top of the shoe or carrier is formed with upstanding flanges 20 and 21 arranged diagonally with respect to the ends of the shoe or carrier, and at sufficient distance apart to admit the tension member 4 of the brake beam and allow it to move transversely between the flanges 20 and 21. So, also, the top of the shoe or carrier is formed with lugs 22 and 23 adapted to be bent down and inwardly, as shown, in order to prevent all danger of the tension member 4 becoming accidentally disengaged from the shoe or carrier under the jars and strains to which the parts in practice are subjected. When the parts are assembled, as shown in Fig-

ures 9, 10 and 11, the tension member 4 may have a free endwise movement with respect to the shoe or carrier.

In the form of the invention shown in Figures 12, 13 and 14, the construction of the shoe or carrier is the same as that illustrated in Figures 9, 10 and 11, except that the lugs 22^a and 23^a are formed as vertical lugs, with holes in their upper ends adapted to receive 10 a cotter pin 25 that will extend between the lugs 22^a and 23^a and will serve to prevent the accidental disengagement of the tension member 4 from the shoe or carrier.

While I have described what I regard as 15 the preferred embodiments of my invention, it will be understood that the details of construction may be varied widely and that features of the invention may be employed without its adoption as an entirety.

Having thus described my invention, what 20 I claim as new and desire to secure by Letters Patent is:

1. A brake beam support, comprising the combination with a brake beam of a supporting track, a shoe arranged between the tension member of the brake beam and the track, said shoe having a lower portion provided with a slot materially wider than the track for retaining it in engagement with the track 25 while permitting a free transverse movement of the shoe with respect to the track, and having on top of said lower portion a seat to receive the tension member of the brake beam, and means for engaging said tension member comprising bendable means integral with said shoe and adapted to retain the shoe on the tension member on both forward and backward movement thereof and to prevent the lifting of the tension member from engagement with the shoe.

2. A brake beam support, comprising the combination with a brake beam having compression and tension members and a strut, of a supporting track, a shoe arranged between 45 the tension member of the brake beam and the track, said shoe having its upper portion provided with a plurality of guards, one of said guards being located opposite and above the end of the brake beam strut, and others 50 of said guards extending transversely of the strut.

3. A brake beam support, comprising the combination with a brake beam having compression and tension members and a strut, 55 of a supporting track, a shoe arranged between the tension member of the brake beam and the track, said shoe having its lower portion provided with a slot to receive the track and having its upper portion provided with 60 a plurality of guards, one of said guards being located opposite and above the end of the brake beam strut, and others of said guards extending transversely of the strut.
